GEORGE F. GAVAED, OF DENVER, COLORADO, ASSIGNOR OF ONE-HALF TO LON E. STEELE, OF DENVER, COLORADO.

HYDROCARBON-BURNER.

1,192,297.

Specification of Letters Patent. Patented July 25, 1916.

Application filed July 27, 1915. Serial No. 42,190.

To all whom it may concern:

Be it known that I, GEORGE F. GAVARD, a citizen of the United States, residing at Denver, in the county of Denver and State of Colorado, have invented certain new and useful Improvements in Hydrocarbon-Burners, of which the following is a specification.

This invention relates to hydro-carbon burners and its object resides in providing a burner of very simple construction which can be readily installed in the fire chamber of an ordinary kitchen range, which is easily cleaned without being removed from the stove and which by substantially complete combustion of the carbon will burn crude oil, commonly known as "distillate," without smoke or odor.

An embodiment of my invention has been illustrated in the accompanying drawings in the various views of which like parts are similarly designated, and in which,

Figure 1 is a plan view of my improved burner, Fig. 2, a longitudinal section taken along the line 2—2 Fig. 1, showing the burner in its operative position in the fire chamber of a kitchen range, Fig. 3, a transverse section taken along the line 3—3 Fig. 1, Fig. 4, an enlarged sectional view of a portion of the vaporizing chamber of the burner, Fig. 5, a transverse section taken along the line 5—5 Fig. 4.

Referring to the drawings by numerical reference characters, 2 designates the base of the burner, which is provided at its front with an upright support 3 to which is attached by means of screws 4, a distance sleeve 5 and a sheet metal plate 6 which, when the device is installed in the fire chamber of a kitchen stove, occupies the opening in the front of the same formerly closed by the fire door. Formed integrally upon the base plate is a mixing chamber 7 composed of an inverted U-shaped conduit 8 the ends of which have in the under surface of the plate, air-inlet ports 9. The mixing chamber has in the top of its horizontal body portion intermediate of its downwardly bent ends, a passage 10 for the outward flow of the combustible mixture, and below the same an opening 12 for the passage of oil into a priming pan 13 which is formed upon the upper surface of the base by an upwardly projecting rib 14. Extending longitudinally

through the horizontal portion of the mixing chamber and through alined openings in the support 3 and the plate 6, is a vapor pipe 15 which by means of elbows 16 is at one of its ends connected with a pipe 17 which extends over the conduit 8 in parallel relation to its horizontal portion and which constitutes the vaporizing chamber of the burner. The vapor feed pipe 15 is at its outer end which is the end opposite to that at which it connects with the vaporizing chamber, closed by means of a screw cap 18 and it has in alinement with the passage 10 of the mixing chamber, a small aperture 19 for the escape of vapor. The screw-cap 18 is enlarged at its outer end to provide a hand-wheel which facilitates its removal and replacement without the use of tools when the burner is being cleaned. The pipe 17 which like the pipe 15 extends through openings in the support 3 and the plate 6, is at its end opposite to that at which it connects with the vapor feed pipe, attached by means of a reduction coupling 20 to a pipe 21 which exteriorly of the stove, connects with an elevated oil reservoir not shown in the drawings. A valve 22 mounted in the coupling is provided to control the flow of liquid from the pipe 21 into the vaporizing chamber 17. A core 23 composed of a bunch of wires 24 tied together by a surrounding spirally wound wire 25, occupies the interior of the pipe 17 and is provided with a handle 26 to permit of its ready removal after the coupling has been detached. The primary object of this core is to provide a spiral passage through which the oil introduced into the vaporizing chamber past the valve 22, flows, thereby retarding its progress through the chamber and permitting every part of the liquid to come in direct contact with the surface of the pipe 17 which is heated by the vapor burning in the combustion space 27 between the mixing chamber and the vaporizing chamber. The wires of which the core is composed are preferably made of copper by reason of its heat retaining properties and after the core has been thoroughly heated it aids in vaporizing the oil flowing spirally along its exterior surface. Another result of the provision of the core is the prevention of backward movement of the oil by the vapor pressure in the feed pipe, which

ordinarily causes the "puffing" which takes place in the majority of oil burners at present in use, and the core furthermore affords a ready means for clearing the vaporizing chamber from carbon and other obstructive matter, it being obvious that by pulling the core out of the pipe by means of its handle after the coupling has been detached therefrom, it will carry with it all the solids which accumulated in the chamber 17. The vapor feed pipe may also be cleaned after removing the cap 18, by scraping it with a suitable tool or by blowing into the end of one of the tubes after both the cap 18 and the coupling 20 are removed. A deflector 28 which is suspended by means of hooks 29 from the pipe 17 over the passage 10 in the mixing chamber, spreads the flame in the combustion space 27, and by clamping the hooks by which it is suspended around the pipe 17, the deflector may be adjusted laterally and is maintained in its adjusted positions by the frictional contact of the hooks with the pipe.

In operation, the burner is placed upon the grate 30 of the stove 31 with its plate 6 occupying the opening 32 which ordinarily affords access to the fire chamber of the same, it being observed that the cap on the feed pipe and the valve in the coupling are thereby placed exteriorly of the stove readily accessible for the purpose of starting or discontinuing combustion in the fire chamber or for cleaning the parts of the burner in the manner hereinbefore described. At initial point in the operation the valve 22 is opened to admit oil from the reservoir connected with the pipe 21 into the vaporizing chamber 17. The oil passing from the pipe 17 into the vapor feed pipe 15 is forced through the aperture 19 of the same and thence drops through the outlet 12 of the mixing-chamber into the priming pan 13 which preferably is filled with asbestos or other suitable absorbent material. After the material in the pan has thus been saturated with oil the liquid is ignited for the purpose of vaporizing the oil flowing continuously through the spiral passage in the pipe 17. The vapors thus produced escape through the aperture 19 into the mixing chamber in which they are thoroughly mixed with the air drawn into the chamber through the inlets 9 which in area exceed the outlet passage 10. The combustible mixture thus produced flows outwardly through the opening 10 into the combustion space 27 in which it is consumed.

Having thus described my improved burner in the best form at present known to me, I desire it understood that modifications in the construction and relative arrangement of its parts may be resorted to within the spirit of my invention as set forth in the following claims.

I claim—

1. A hydro-carbon burner comprising a base, a mixing-chamber thereon, having an air-inlet and a vapor-outlet, a plate connected with the base, to occupy an opening in the side of a stove in whose fire-chamber the burner is installed, a vaporizing pipe and a therewith connected apertured vapor-feed pipe extending respectively over and through the mixing-chamber and both projecting through openings in the said plate, and means for the connection of the vaporizing pipe with a source of fuel-supply, exteriorly of the plate. 70 75

2. A hydro-carbon burner comprising a base, a mixing-chamber composed of a conduit spaced from the base and connected at its ends with inlets in the under surface of the same, the said chamber having intermediate of the said inlets, a vapor outlet, a vaporizing pipe and an apertured vapor-feed pipe connected at one of their ends, and extending respectively longitudinally over and longitudinally through the mixing-chamber, a closure for the opposite end of the feed pipe, and means for the connection of the opposite end of the vaporizing pipe with a source of fuel-supply. 80 85 90

3. A hydro-carbon burner comprising a base having a priming-tray, a mixing-chamber composed of a conduit spaced from the base and connected at its ends with inlets in the under surface of the same, the said chamber having intermediate of the said inlets, a vapor outlet, and an outlet for the discharge of liquid into the priming-tray, a vaporizing pipe and an apertured vapor-feed pipe connected at one of their ends, and extending respectively longitudinally over and longitudinally through the mixing-chamber, a closure for the opposite end of the feed pipe and means for the connection of the opposite end of the vaporizing pipe with a source of fuel-supply. 95 100 105

4. The combination with the fire-chamber of a stove, of a hydrocarbon burner including a mixing chamber in the fire-chamber, having an air-inlet and a vapor-outlet, a vaporizing pipe and an apertured vapor-feed pipe connected within the fire chamber and extending respectively over and through the mixing chamber, the said pipes projecting at their unconnected ends exteriorly of the fire chamber, means for connecting the exterior end of the vaporizing pipe with a source of fuel supply, and a removable means closing the exterior end of the vapor-feed pipe. 110 115 120

5. The combination with the fire chamber of a stove, of a hydro-carbon burner including a vaporizing pipe and an apertured vapor-feed pipe connected within the fire chamber and projecting at their unconnected ends exteriorly of the fire-chamber, means for connecting the exterior end of the va- 125 130

vaporizing pipe with a source of fuel supply, and a removable means closing the exterior end of the vapor-feed pipe.

6. A hydro-carbon burner comprising a plate adapted to occupy an opening in the side of a stove in whose fire-chamber the burner is installed, a vaporizing pipe and a therewith connected apertured vapor feed-pipe projecting through openings in the 10 said plate, means for connecting the exterior portion of the vaporizing pipe with a source of fuel supply, and a removable means closing the exterior end of the feed-pipe.

7. The combination with the fire-chamber 15 of a stove, of a hydrocarbon burner including a vaporizing pipe and an apertured vapor-feed pipe connected within the fire chamber and projecting at their unconnected ends exteriorly of the fire-chamber, detachable means for connecting the exterior 20 end of the vaporizing pipe with a source of fuel supply, a removable means closing the exterior end of the vapor-feed pipe, and an exteriorly channeled core loosely disposed 25 within the vaporizing pipe for removal

through its exterior end after the means which connect the said pipe with the source of fuel-supply have been detached.

8. A hydrocarbon burner comprising a plate adapted to occupy an opening in the 30 side of a stove in whose fire-chamber the burner is installed, a vaporizing pipe and a therewith connected apertured vapor-feed pipe projecting through openings in the said plate, detachable means for connecting the 35 exterior portion of the vaporizing pipe with a source of fuel supply, a removable means closing the exterior end of the feed-pipe, and an exteriorly channeled core loosely disposed within the vaporizing pipe, for removal 40 through its exterior end after the means which connect the said pipe with the source of fuel supply have been detached.

In testimony whereof I have affixed my signature in presence of two witnesses.

GEORGE F. GAVARD.
